Int. Cl. C11d 3/066

U.S. Cl. 252—137

5 Claims

ABSTRACT OF THE DISCLOSURE

Liquid detergent hard surface cleaning compositions containing 0.25% to 4% of specific short-chain water-soluble synthetic detergent; 1% to 6% of a water-soluble builder or mixture of builders; 1% to 10% of specific organic solvents or mixture of solvents; and water.

BACKGROUND OF THE INVENTION

This invention relates to liquid detergent compositions. More particularly, this invention relates to liquid detergent compositions suitable for hard surface cleaning in a no-rinse method with improved cleaning and without an unacceptable filming or streaking problem.

In general, liquid detergent compositions are well known in the art and many such compositions have been used in the past for cleaning hard surfaces such as glass, painted walls, woodwork and the like. Generally when such compositions are applied to the above surfaces without a subsequent rinse, they leave a film after their cleaning function has been performed. This residual film, when it contains an organic detergent, can act almost as a trap and collects dirt. The surface thus cleaned with such a composition does not appear clean and can become dirty again even more rapidly than the same surface would become dirty in the absence of the residual film.

Many attempts have been made to produce a so-called volatile detergent composition. Theoretically, such a volatile composition when applied to a surface would perform its cleaning function and then completely evaporate, leaving the clean surface free of any residual film which would enhance the subsequent collection of dirt or soil. Volatile compositions have been prepared in the past which will substantially evaporate after use leaving the surface devoid of any noticeable residual film but, in general, such detergent compositions will not adequately or sufficiently clean the surface as desired or present other negatives such as inflammability or noxious odor.

One of the principal objects of the present invention is to provide a novel liquid detergent composition which effectively cleans hard surfaces when used in a no-rinse method without leaving an objectionable residual film.

It is a further object of the present invention to provide liquid detergent hard surface cleaner compositions containing specific synthetic detergent and specific organic solvents which have an increased cleaning ability and which will also leave a minimum and almost invisible film deposit on the surface.

Other objects and advantages of the present invention will be readily apparent to one skilled in the art from the following description.

SUMMARY OF THE INVENTION

The objects of the present invention are achieved by a liquid detergent composition consisting essentially of an aqueous medium containing specific short-chain synthetic detergents, a builder or combination of builders and an organic solvent or mixture of organic solvents which are sufficiently hydrophobic to dissolve oily soils, e.g., grease.

The present invention is a novel liquid detergent com-

2

position consisting essentially of from about 0.25% to about 4.0% by weight of a compatible short-chain water-soluble synthetic detergent selected from the group consisting of: (1) 3-[N,N'-dimethyl-N-alkylammonio]-2-hydroxypropane-1-sulfonate wherein said alkyl group contains about 10 carbon atoms, (2) 2-(N,N',N"-trimethylammonio) decanoate, (3) alkali metal straight chain alkyl benzene sulfonates wherein said alkyl group contains from about 6 to about 8 carbon atoms, and (4) alkali metal straight chain alkyl sulfates wherein said alkyl group contains from about 6 to about 12 carbon atoms, from about 0.5% to about 6.0% by weight of a water-soluble builder, e.g., a builder selected from the group consisting of water-soluble polyphosphonates, tripolyphosphates, orthophosphates, borates, pyrophosphates, polymeric carboxylates and aminopolycarboxylates and mixtures thereof, from about 1.0% to about 10.0% by weight of an organic solvent or mixture of solvents selected from the group consisting of propylene glycol butoxy ether, propylene glycol isobutoxy ether, and dipropylene glycol butoxy ether and mixtures thereof; and the balance water.

Among the detergents which have been found useful as the active detergent agent in the compositions of the present invention and which are clearly within the contemplation of this invention are the following examples: the alkali metal (e.g., sodium and potassium), ammonium and substituted ammonium (e.g., lower alkanol ammonium) hexyl, octyl, nonyl, decyl, undecyl and dodecyl sulfates; linear alkylbenzene sulfonates in which the alkyl radical contains from about 6 to about 8 carbon atoms, and sulfates of long chain alcohols containing from about 6 to about 12 carbon atoms.

Other suitable synthetic detergents are 3-(N,N'-dimethyl - N - decylammonio)-2-hydroxypropane - 1 - sulfonate and 2-(N,N',N"-trimethylammonio) decanoate. These detergents are unique in that compositions which contain them adhere to vertical surfaces when sprayed onto said surfaces from a spray device or aerosol container and do not run down. This is very desirable since it keeps the compositions where the soil is while the vertical surface is wiped and prevents streaking on clean walls.

From the standpoint of filming, the best detergents are a C₆—C₁₀ alkyl sulfate, 3 - (N,N' - dimethyl - N - decylammonio)-2-hydroxypropane-1-sulfonate, 2 - (N,N',N"-trimethylammonio) decanoate, and C₆—C₈ alkyl benzene sulfonates.

From the standpoint of cleaning, the best detergents are 3 - (N,N' - dimethyl - N - decylammonio) - 2 - hydroxypropane-1-sulfonate, C₆—C₈ alkyl benzene sulfonates, and 2-(N,N',N"-trimethylammonio) decanoate.

The anionic and zwitterionic detergents mentioned above can be used singly or in combination in the practice of the present invention. The synthetic detergent comprises from about 0.25% to about 4.0% by weight of the total composition. If more than about 4.0% is used an undesired streaking and filming problem may result and if less than about 0.25% is used the desired level of cleaning will not be achieved. A preferred range of from about 0.50% to about 2.0% by weight of a synthetic detergent as described above will yield the best results of the invention.

The builders which can be utilized in the practice of the present invention to give the desired cleaning performance without attendant excessive filming and streaking problems are selected from the group consisting of water-soluble polymeric carboxylates, polyphosphonates, tripolyphosphates, orthophosphates, borates, pyrophosphates, and amino polycarboxylates.

Suitable builders include the alkali metal (e.g., sodium and potassium) and ammonium (including substituted ammoniums, e.g., triethanolammonium) amino polycarboxylates, organic polyphosphonates, polymeric carboxy-

lates, pyrophosphates, orthophosphates, borates and tri-polyphosphates. Suitable amino polycarboxylates are those described in U.S. Pat. 3,329,617 and 3,336,233. Suitable polyphosphonates are those described in U.S. Pats. 3,329,617; 3,336,233; 3,332,880; 3,213,030; 3,400,148; 3,400,176; and 3,400,151 and copending U.S. applications: Roy, Ser. No. 266,055, filed Mar. 18, 1963; Roy, Ser. No. 493,925, filed Mar. 18, 1963; Quimby, Ser. No. 517,073, filed Dec. 28, 1965; Quimby and Prentice, Ser. No. 587,417, filed Oct. 18, 1966; Quimby, Ser. No. 605,606, filed Dec. 29, 1966; Curry, Ser. No. 717,999, filed Apr. 1, 1968; Nicholson and Campbell, Ser. No. 694,002, filed Dec. 27, 1967; Nicholson and Campbell, Ser. No. 694,003, filed Dec. 27, 1967; and Prentice and Quimby, Ser. No. 694,106, filed Dec. 28, 1967. Suitable polymeric carboxylates are disclosed in U.S. Pat. 3,308,067. All of the above patents and applications are incorporated herein by reference. Preferred builders are sodium orthophosphate, sodium nitrilotriacetate, potassium pyrophosphate, potassium tripolyphosphate and sodium or potassium ethane-1-hydroxy-1,1-diphosphonate and similar derivatives.

Other suitable builders are disclosed hereinafter in the examples.

The builders or builders mixture selected from the group above comprises from about 0.5% to about 6% by weight of the total composition. If more than about 6% by weight is used, then an undesired filming and streaking problem is observed and if less than about 0.5% weight is used the desired cleaning results of the invention will not be realized. If about 0.75% to 2.5% builders by weight of the total composition is used the best cleaning and non-filming results of the invention are achieved.

The solvent which can be used, either alone or in combination, in the practice of this invention to aid in grease removal are selected from the group consisting of propylene glycol isobutoxy ether, propylene glycol butoxy ether, and dipropylene glycol butoxy ether. These solvents cause either cleaning or filming and streaking problems when used with most conventional detergents. However, in combination with the specific detergents described hereinbefore, good cleaning filming and streaking characteristics are obtained.

The solvent or solvent mixture of this invention comprises from about 1% to about 10% by weight of the total composition. If more than about 10% by weight is used, the resulting solvent based cleaner is undesirably capable of removing paint and finishes from the surfaces it is used on. Furthermore, such large amounts of solvents present an odor problem. If less than about 1% by weight is used, then the desired cleaning function is not adequately performed. A preferred range of solvent is from about 4% to about 8% by weight.

The compositions of this invention can also contain certain hydrotropes such as sodium, potassium and ammonium toluene sulfonates, xylene sulfonates, benzene sulfonates, and cumene sulfonates in an amount ranging from about 1/2% to about 3% of the composition. These hydrotropes help to keep the formula in a single phase.

Miscellaneous materials such as coloring agents, aerosol propellants, perfumes, pH buffers, and other materials which are well known as constituents in liquid detergent compositions and which are compatible in the formulations of the present invention can also be present in minor amounts.

The various constituents of the liquid detergent compositions of the present invention can be admixed in any sequence to achieve the desired objects as stated above. It is preferred, however, for ease of solubility, to add the components in the following order at temperatures of between about 40° F. and about 100° F. with constant agitation: water, builder, solvents, detergent and, if any, the optional components.

The liquid detergent compositions of this invention can be utilized either full strength or in dilute solutions. A preferred method of application is in the form of a spray

or aerosol for small spots and for small spot cleaning, full strength is recommended. When one wishes to apply the compositions over large surfaces utilizing a sponge, mop, or brush, then dilution is suggested although this is dependent on the individual situation's requirements.

The following examples illustrate in detail the manner in which the invention can be practiced. However, the invention is not confined to the specific limitations set forth in the individual examples but, rather, to the scope of the appended claims.

PREFERRED EMBODIMENTS

Example I

Liquid detergent compositions were prepared according to the following general formula:

	Percent
Water soluble synthetic detergent	2.0
Propylene glycol butoxy ether	6.0
Trisodium orthophosphate dodeca-hydrate	2.0
Ammonium cumene sulfonate	1.5
Soft water	Balance to 100

In order to evaluate the cleaning and resulting streaking filming characteristics of this composition the following tests were conducted.

Cardboard panels, about 2 1/2" x 3", were painted with three coats of paint, divided into two groups, and then the two groups were respectively soiled in a standard manner with a low fat soil and a high fat soil. Two of the soiled panels which had been soiled with the same soil are then placed in the Gardner Straight Line Washability Machine manufactured by Gardner Laboratory Inc., Bethesda, Md., which utilizes sponges as the cleaning device. Five ml. of each of the two compositions to be compared are placed on their respective sponges and the machine is run until a cleaning difference is noted or until about 75% of the said soil is cleared by both compositions. The samples are then rerun on other similarly soiled panels reversing the positions of the compositions and the sponge. The grading is done visually based on the amount of soil removed. The grades are equal, slightly better, slightly poorer, better, worse, much better and much worse.

Filming grades were determined by spraying the composition on a black ceramic tile and a mirror, wiping the tile and mirror clean with a soft dry cloth and allowing them to dry. They are graded by judges as heavy, moderate, light, trace and no filming.

The following table shows the comparison of different chain length sodium alkylbenzene sulfonates.

	C ₁₂	C ₁₀	C ₈	C ₆	C ₄
Cleaning:					
High fat.. Basis	Slightly	Better	Much	Much	better.
Low fat...do	poorer.	better.	better.	better.	better.
Filming	Moderate	Equal	Better	Equal	Equal
	heavy.	Moderate	Light	Trace	Trace
			light.	light.	light.

C₆ alkylbenzene sulfonate is preferred and C₄ and C₈ alkylbenzene sulfonates are next best.

The following table shows the comparison of different chain length sodium alkyl sulfates.

	Coconut ¹	C ₁₀	C ₈	C ₆
Cleaning	Basis	Equal	Equal	Equal
Filming	Light	Light	Trace	light.

¹ Coconut refers to the following chain length distribution: 2%—C₁₀; 66%—C₁₂; 23%—C₁₄; and 9%—C₁₆.

C₈ alkyl sulfate is preferred and C₆ and C sulfates are next best.

Similar tests with 3-[N,N'-dimethyl-N-decylammonio]-2-hydroxypropane-1-sulfonate (C₁₀HAPS) and 2-

(N,N',N"-trimethylammonio)decanoate (Dupont BDO) gave the following results.

	C ₁₀ HAPS	C ₁₂ HAPS	BDO	Sodium octylbenzene sulfonate	5
Cleaning	Equal	Equal	Equal	Basis.	
Filming	Trace-light	Heavy	Trace-light	Light.	

Similar results are obtained when 1% detergent is used instead of 2%.

The C₁₀HAPS and BDO formulas did not immediately run down when sprayed from a mechanical sprayer onto a vertical surface.

Example II

The following compositions all have the general formula:

	Percent
Water soluble synthetic detergent	2.0
Propylene glycol isobutoxy ether	3.0
Dipropylene glycol butoxy ether	3.0
Builder	2.0
Hydrotrope	2.0
Water	Balance

Composition	Detergent	Builder	Hydrotrope
1	Potassium hexylbenzene sulfonate	Sodium tripolyphosphate	Sodium toluene sulfonate.
2	Sodium octylbenzene sulfonate	Potassium ethane-1,2-triphosphonate	Potassium toluene sulfonate.
3	Ammonium nonylbenzene sulfonate	Triethanolammonium poly(itaconato-acrylate) (4:1 on a molar basis) (specific viscosity of 1% by weight, in dimethyl formamide at room temperature—.40) (equivalent weight—65.8).	Ammonium toluene sulfonate.
4	Potassium hexylbenzene sulfonate	Potassium ethane-1-hydroxy-1,2-triphosphonate.	Sodium xylene sulfonate.
5	Sodium r-octylbenzene sulfonate	Ammonium ethane-2-hydroxy-1,1,2-triphosphonate.	Potassium xylene sulfonate.
6	Sodium r-hexylbenzene sulfonate	Tripotassium ethane-1-hydroxy-1,1-diphosphonate.	Ammonium xylene sulfonate.
7	Potassium nonyl sulfate	Sodium nitrilotriacetate	Sodium benzene sulfonate.
8	Sodium 4-nonyl sulfate	Potassium pyrophosphate	Potassium benzene sulfonate.
9	Sodium olefin sulfonate	Ammonium methylene-diphosphonate	Ammonium benzene sulfonate.
10	Potassium salt of the detergent of Composition 9.	Sodium ethylene-1,1-diphosphonate	Sodium cumene sulfonate.
11	Sodium nonyl polyethoxylate (4 moles) sulfate	Sodium N-(2-hydroxy-ethyl)-ethylenediaminetriacetate	Potassium cumene sulfonate.
12	Potassium decyl polyethoxylate (2 moles) sulfate	Potassium N-(2-hydroxyethyl)-nitrilotriacetate	Triethanolammonium cumene sulfonate.
13	Sodium decyl sulfate	Potassium isopropylidene diphosphonate	Triethanolammonium benzene sulfonate.
14	Potassium undecyl sulfate	Ammonium ethylenediphosphonate	Triethanolammonium xylene sulfonate.
15	Potassium tridecyl sulfate	Potassium hydroxymethylenediphosphonate	Triethanolammonium toluene sulfonate.
16	1:1 mixture by weight of sodium hexylbenzene sulfonate and sodium octyl sulfate	1:1 mixture by weight of ammonium propane-1,1,3,3-tetraphosphonate and ammonium propane-1,2,2,3-tetraphosphonate	Morpholinium cumene sulfonate.
17	1:1 mixture by weight of sodium octylbenzene sulfonate and sodium decyl sulfate	Ammonium propane-1,1,3-tetraphosphonate	Morpholinium xylene sulfonate.
18	3-(N,N'-dimethyl-N-decylammonio)-2-hydroxypropane-1-sulfonate	1:1 mixture by weight of sodium carboxylidiphosphonate and sodium hexametaphosphonate	Morpholinium toluene sulfonate.
19	Potassium hexylbenzene sulfonate	1:1 mixture of sodium borate and potassium pyrophosphate	1:1 mixture of sodium xylene sulfonate and sodium toluene sulfonate.

In addition to the preferred embodiments described herein, other arrangements and variations within the spirit and scope of the invention and the appended claims will occur to those skilled in the art.

What is claimed is:

1. A novel liquid detergent hard surface no-rinse cleaning composition consisting essentially of:

- (A) from about 0.25% to about 4.0% by weight of a compatible short-chain water-soluble synthetic detergent selected from the group consisting of: (1) 3-(N,N-dimethyl-N-decylammonio)-2-hydroxypropane-1-sulfonate (2) 2-(N,N',N"-trimethylammonio)decanoate, and (3) alkali metal straight chain alkylbenzene sulfonates wherein said alkyl group contains from about 6 to about 8 carbon atoms;
- (B) from about 0.5% to about 6.0% by weight of a water-soluble builder selected from the group consisting of water-soluble polyphosphonates, tripolyphosphates, orthophosphates, borates, pyrophosphates, polymeric carboxylates, and amino poly-carboxylates and mixtures thereof;

phates, polymeric carboxylates, and amino poly-carboxylates and mixtures thereof;

(C) from about 1.0% to about 10% by weight of an organic solvent or mixture of solvents selected from the group consisting of propylene glycol butoxy ether, propylene glycol isobutoxy ether, and dipropylene-glycol butoxy ether, and mixtures thereof; and

(D) the balance water.

2. The composition of claim 1 wherein the water-soluble synthetic detergent is a linear alkylbenzene sulfonate wherein the alkyl group contains from about 6 to about 8 carbon atoms.

3. The composition of claim 1 wherein the builder is trisodium orthophosphate.

4. The composition of claim 1 wherein the organic solvent is propylene glycol butoxy ether.

5. The composition of claim 1 wherein the water-soluble synthetic detergent is selected from the group consisting of 3-(N,N'-dimethyl-N-decylammonio)-2-hydroxypropane-1-sulfonate and 2-(N,N',N"-trimethylammonio)decanoate.
